ROBERT A. CURRIE, OF SYRACUSE, NEW YORK, ASSIGNOR TO R. E. DIETZ COMPANY, OF NEW YORK, N. Y.

COMBUSTION CONE OR PROTECTOR FOR TORCHES

Application filed March 29, 1929. Serial No. 350,935.

This invention relates to combustion cones or flame protectors for lamps, particularly of the torch type which are commonly used in places where they are exposed to out-door weather conditions, and which are not provided with chimneys, globes or the like, such as used in other types of lamps and lanterns.

One object of the invention is to provide a practical and simple device for use on torch lamps which, in operation, will effectually direct the air to the flame so as to properly support combustion and prevent the flame from being extinguished.

Another object is to provide a device which will effectually keep the torch burning during strong winds, shifting air currents and other adverse weather conditions.

Other objects of the invention are to provide a device of simple and practical construction which will enable the efficient and reliable use of torches out of doors and prevent their flames from being blown out or being extinguished by rain or snow; also to provide a combustion cone or device which provides a flame chamber of such form and dimensions as to insure the necessary supply of air to the flame to sustain the flame and revive it in intensity following sudden shifts in the wind; also to provide a combustion cone or flame protector which will keep the torch burning under all weather conditions; and also to provide a combustion cone or flame protector which is of the improved construction and has the advantages herein-after described and set forth in the claims.

In the accompanying drawings:

Fig. 1 is a fragmentary elevation on a reduced scale, of a torch lamp provided with a combustion cone or flame protector embodying my invention.

Fig. 2 is a plan view, full size, of the combustion cone or protector partly in section on line 2—2, Fig. 1.

Fig. 3 is a fragmentary elevation of the torch showing the cone or protector in section on line 3—3, Fig. 2.

Fig. 4 is a fragmentary elevation of the torch showing the holding device for the combustion cone moved out of its holding position.

Fig. 5 is a sectional elevation showing a slightly modified embodiment of the invention.

Referring now to the drawings:

10 represents the upper portion of the body or front of a torch lamp and 11 represents the wick tube or burner thereof which projects from the top of the torch body and through which the usual wick 12 passes. The burner shown has a cylindrical, tubular upper end portion 13 and a circumferential enlargement or flange 14 at the base of the cylindrical portion of the burner and which is adapted to bear or seat against the top of the font. These parts are of known construction, and as usual, the burner may be provided with a threaded lower end portion by which it is adapted to be removably screwed into a threaded hole in the top of the font.

15 represents the combustion cone or protector. This device is hollow and adapted to surround the upper portion of the burner or wick tube 11, and is provided with an annular, preferably circular, wall which increases in diameter upwardly, and an imperforate top plate or wall 16. As shown, and this is the preferred construction, the circular wall of the cone or protector is of stepped formation, having three substantially cylindrical portions 17, 18 and 19, which are of successively larger diameter from the lower to the upper end of the device, and are connected by annular shoulder portions. Preferably, the lower end 20 of the circular wall extends inwardly and has an upstanding or upturned cylindrical sleeve 21 which surrounds and is adapted to be slipped on the cylindrical portion 13 of the burner tube, whereby the combustion cone or protector is retained in place on the burner resting at its lower end 20 on the annular enlargement 14 of the burner.

Thus, the combustion cone or protector provides a combustion chamber into which the upper end of the burner tube extends, and which forms an annular air space 22 surrounding the upper end portion of the burner 11.

As shown, the circular wall and top 16 of the protector are formed of separate sheet

metal pieces or stampings secured together by an interlocking or other suitable joint at the junction of the upper end of the circular wall with the outer periphery of the top plate 16, but the combustion cone or protector could be made of other suitable construction.

The combustion cone or protector is provided in its circular wall with holes or openings of such size, disposition and form as to insure the proper supply of air to the burner to support combustion and to permit the flame to issue or extend through the openings out of the combustion cone or protector. As shown in Figs. 1-4, the intermediate cylindrical portion 18 of the circular wall is provided with a plurality of circular holes 23 which are spaced equidistantly around this portion 18 of the circular wall, and the uppermost cylindrical portion 19 of the circular wall is provided with elongated openings 24 which are also disposed equidistantly around this largest portion 19 and are preferably of substantially larger area than the holes 23. Preferably the openings are located so that the openings 24 alternate with or are located between the holes 23 circumferentially of the protector. The lower and smaller holes 23 are preferably located with respect to the burner, substantially at the elevation shown, that is so that the lower edges of the holes 23 are at substantially the same elevation or slightly above the top edge of the burner or wick tube 11. The large openings 24 are thus disposed at a substantial elevation above the top of the burner or wick tube 11.

With the combustion cone or protector formed and proportioned substantially as shown, the necessary supply of air to the burner to support combustion is insured and the flame will burn within the protector, and the tongues of flame will protrude or extend out through the large, upper openings 24 so that the torch will furnish the intended illumination. Nevertheless this construction prevents the flame from being extinguished by strong winds or drafts. In the use of the torch, the flame varies with wind currents, and even in a strong breeze it may first flare up on one side and then suddenly veer or shift to another side of the device. The large flame or combustion chamber provided, which extends a substantial height above the upper end of the burner tube and at its widest upper portion is of much greater cross sectional area than the burner tube and wick, and which has side openings such as shown, always insures an adequate supply of air for the flame to sustain itself and revive in intensity following sudden shifts of wind. The flame will not be extinguished or in effect sheared off by blasts of air through the openings in the sides of the combustion cone or protector, as would be the case with a protector providing a small flame chamber in which the flame openings would be necessa-

rily disposed close to and substantially at or only slightly above the level of the top edge of the wick tube.

The combustion cone or protector shown in Fig. 5 is of substantially the same form and dimensions as that shown in Figs. 1-4 and above described, but in the Fig. 5 construction, an annular row of perforations 25 is provided in the reduced lowermost cylindrical portion 17 of the cone, below the level of the top of the burner tube, in addition to the openings in the larger, intermediate and top cylindrical portions 18 and 19 of the cone or protector. In this construction a larger number of holes 26 are shown in the intermediate cylindrical portion 18 of the cone or protector, these openings, however, being preferably of about the same size, and disposed at substantially the same elevation as shown in the construction first described. The combustion cone or protector shown in Fig. 5 is also preferably provided with an internal flange or deflector ring 27 which projects inwardly from the circular wall of the cone between the two rows of holes 25 and 26 toward the burner tube 11. This flange may be suitably secured to the circular wall of the combustion cone or protector, and as shown, its inner periphery is spaced from the burner tube 11 so as to leave an annular air passage 28 between the inner edge of the deflector 27 and the burner tube through which air entering through the bottom row of perforations 25 can flow upwardly around the burner tube into the large combustion or flame space in the combustion cone or protector. The deflector 27 is preferably formed as shown, that is, it is provided near its inner edge with a circumferential groove, and the inner edge of the deflector 27 tapers upwardly and inwardly toward the burner tube. In this construction, air is taken in through the bottom row of perforations and is directed through the passage 28 to the base of the flame so as to support combustion.

Both constructions of the cone or protector shown and described provide a combustion chamber amply large and having openings arranged so as to keep the torch burning during heavy winds, and prevent a shearing action of the wind which would, in effect, cut or tear the flame from the wick. Besides, the device performs the important function of feeding the necessary supply of air close to the top of the wick tube. The flame chamber is large enough for the flame to build up and in a way be supported by the side walls of the cone. Then when changing air currents are set up, as for example, by rapidly passing vehicles, there is a space around the flame sufficient to permit it to recover its balance. The imperforate top of the combustion cone or protector pre-

- vents rain or snow from falling on the wick and quenching the flame.
- The combustion cone or protector, in either of the forms illustrated and described, 5 may be retained in place on the torch against accidental displacement by suitable means. For example, as shown, the lower end of the combustion cone or protector, as before explained, is adapted to be slipped down over the upper end of the burner tube and against the flange 18 of the burner, and it is releasably held in place on this seat by a bail or handle 30. The ends of the legs of this bail are pivoted in holes in the sides of the wick 10 tube below the lower end of the protector, and the legs of the bail, when the latter is in the upright position shown in Fig. 1, are adapted to snap into shallow notches 31 in the periphery of the upper end of the combustion cone or protector, see Fig. 2. The legs of the bail have portions which incline inwardly just above the edge of the cone or protector, as indicated, so that when the legs are seated in the notches 31 in engagement 15 with the edge of the protector, the bail will firmly hold the protector on its seat on the burner or wick tube. The bail can be readily disengaged from the protector simply by swinging the bail downwardly to a laterally projecting position, by doing which the legs of the bail will be sprung out of holding engagement with the notches 31 and will release the combustion cone or protector, which can then be pulled or lifted off of 20 the burner or wick tube.
- The bail 30 is preferably the carrying bail or handle for the torch.
- I claim as my invention:
1. The combination with a torch having a wick tube, of a hollow protector which provides a combustion chamber surrounding the upper end of said wick tube and having flame openings in its sides at an elevation above the upper end of the wick tube, and air admission holes at a lower elevation, the cross sectional area of the portion of said chamber in which said flame openings are located being more than twice that of the wick tube.
  2. The combination with a torch having a burner, of a hollow protector which provides a combustion chamber surrounding the upper end of said burner, and having flame exit openings in its sides at an elevation above the upper end of the burner, and means for the admission of air to said chamber below said flame exit openings and adjacent the upper end of the burner, the cross sectional area of the portion of said chamber in which said exit flame openings are located being more than twice that of the burner.
  3. The combination with a torch having a wick tube, of a hollow protector which provides a combustion chamber surrounding the upper end of said wick tube and having
- flame exit openings in its sides at an elevation above the upper end of the wick tube, and an imperforate top, and means for the admission of air to said chamber below said flame exit openings and adjacent the upper end of the wick tube, the cross sectional area of the portion of said chamber in which said flame openings are located being more than twice that of the wick tube. 70
4. The combination with a torch burner, of a hollow protector which covers the upper end of the burner and has lower, intermediate and top portions at different elevations which materially increase in cross sectional area from the bottom to the top portion, and said protector having flame exit openings in the sides of said top portion, and air admission holes in a lower portion. 75
  5. The combination with a torch burner, of a hollow protector which covers the upper end of the burner and has an annular wall of stepped formation which increases in diameter from its lower to its upper portion, said upper and lower portions being of materially different cross sectional area, said annular wall having flame exit openings in its large upper portion and air admission holes in a lower portion. 80
  6. The combination with a torch burner, of a hollow protector which covers the upper end of the burner and is provided in its sides with openings, and a retaining device movably connected to the torch and arranged to engage said protector for releasably retaining it in place on the torch. 95
  7. The combination with a torch burner, of a hollow protector which covers the upper end of the burner and is provided in its sides with openings, and a bail pivoted to the torch and movable into holding engagement with said protector for releasably retaining it in place on the torch. 100
  8. The combination with a torch burner, of a hollow protector which covers the upper end of the burner and is provided in its sides with openings and at its lower end with a sleeve which surrounds and removably fits the upper end of the burner, and a retaining device movable to and from holding position for releasably holding it on said burner. 110
  9. The combination with a torch having a burner, of a hollow protector which provides a combustion chamber for the burner flame having an upper portion of materially larger cross sectional area than the burner, and having flame openings in the sides of said upper portion, and an overhanging edge which projects outwardly from the protector above said flame openings. 120
  10. The combination with a torch having a wick tube, of a hollow protector which encloses the upper end of the wick tube and provides a combustion chamber for the torch flame having a reduced lower portion surrounding the upper end of the wick tube and 130

5 a portion of materially larger cross sectional area above said reduced portion, and having flame exit openings in the sides of said larger portion and at an elevation above the upper end of the wick tube, and means for the admission of air to said combustion chamber below said flame exit openings.

10 11. The combination with a torch having a wick tube, of a hollow protector which encloses the upper end of the wick tube and provides a combustion chamber for the torch flame having a reduced lower portion surrounding the upper end of the wick tube and a portion of materially larger cross sectional area above said reduced portion, and having flame exit openings in the sides of said larger portion and at an elevation above the upper end of the wick tube, and air admission holes below said flame exit openings.

15 12. The combination with a torch having a burner, of a hollow protector which provides a combustion chamber in which the torch flame burns and which increases in horizontal diameter upwardly and the upper portion 20 of which is of materially greater cross sectional area than the lower portion, said chamber having flame exit openings in the sides of said large upper portion at an elevation above the burner, and an air inlet for said 25 combustion chamber at a lower elevation than said flame openings.

30 13. The combination with a torch having a wick tube, of a hollow protector which surrounds the upper end of the wick tube and 35 has a reduced lower portion annularly spaced from the wick tube and a portion of materially larger cross sectional area above said reduced portion, and which has flame exit openings in the sides of said larger portion and 40 at an elevation above the upper end of the wick tube, a deflector ring partially closing the annular space between the wick tube and the wall of the reduced lower portion of the protector, and means for the admission of 45 air to said protector above and below said deflector ring.

ROBERT A. CURRIE.
